UNITED STATES PATENT OFFICE.

GEORGE H. CLARK, OF CAMPELLO, MASSACHUSETTS, ASSIGNOR TO THE CLARK RELASTING AND SHOE-TREEING COMPANY, OF PORTLAND, MAINE.

LAST.

SPECIFICATION forming part of Letters Patent No. 388,830, dated September 4, 1888.

Application filed March 27, 1888. Serial No. 268,620. (No model.)

To all whom it may concern:

- Be it known that I, GEORGE H. CLARK, of Campello, county of Plymouth, State of Massachusetts, have invented an Improvement in 5 Lasts, of which the following description, in connection with the accompanying drawings, is a specification, like letters on the drawings representing like parts.
- This invention has for its object to construct 10 a last for boot and shoe work, the last being especially adapted to be used as a follower or second last which is fitted into the partially-made boot or shoe, the first one having been withdrawn.
- 15 In accordance with this invention the last is made as a single block, which is sawed or divided vertically by a single cut across the shank, to present a heel portion and a fore part, the latter including the toe and instep portions. The division-line is made diagonally, inclining toward the heel from the instep to the shank, so that each part has one inclined abutting wall, and the heel portion will be wedge shaped—that is, wider at the top 20 and narrower at the bottom. The heel portion and fore part each have a hole (see dotted lines) to receive pins or other tools adapted to spread or separate the said parts one from the other.
- 25 Figure 1 shows in side elevation a last cut to present the fore part and heel portion in accordance with the invention, and Fig. 2 a modification to be referred to.
- The last is made as a single block, in any 30 usual shape, which is thereafter cut or divided, as by a single cut along the line *a*, to present the heel portion *b* and the fore part *c*, the said fore part *c* including the toe portion, instep, and shank. The division-line *a* (see Fig. 1) 35 extends from the instep to the shank diagonally toward the heel, so that the two parts *b* *c* each have an inclined abutting wall, and the heel portion *b* is wedge-shaped, it being wider at the top.
- 40 In the practice of my invention the fore part *c* is placed in the boot or shoe, the said part
- being pushed in as far as possible by hand or by the aid of a suitable machine, after which the heel portion (wedge shaped, as described) is placed in the boot or shoe and pushed into 50 position, if necessary, crowding the fore part farther forward.
- The heel portion may be removed at any time desired and the fore part remain in the boot or shoe, it being seen that the counter 55 practically includes the space left by the heel portion when removed, thereby rendering the heel portion *b* superfluous when the shoe is undergoing some steps of the manufacture. By this construction it will be seen that the 60 fore part being made as a single block may be inserted, and as there is no independent instep-block the shoe cannot become creased and the lining injured; and furthermore the fore part may be very readily removed without strain 65 upon the upper by first removing the heel portion, and then removing the fore part rearwardly toward the heel to withdraw it.
- In Fig. 2 the division-line *a* is located at a point farther forward, so as to include a larger 70 heel portion, and in this instance the holes 20 are omitted.
- The heel portion and fore part each have a hole, 20, bored in it, as shown by dotted lines, Fig. 1, which receives a pin or other tool attached to any suitable spreading device, by which the heel and fore parts of the last are separated one from the other, such a machine being shown in the application, Serial 75 No. 268,620, filed by me March 27, 1888. 80
- I claim—
- In a two-part last for boot and shoe work, the heel portion and fore part separated along the line *a*, and each having a vertical tool-receiving hole, 20, substantially as described. 85
- In testimony whereof I have signed my name to this specification in the presence of two subscribing witnesses.

GEORGE H. CLARK.
